UNITED STATES PATENT OFFICE.

JOSEPH L. WRIGHT, OF CLEVELAND, OHIO, ASSIGNOR, BY MESNE ASSIGNMENTS, TO
JAMES R. GARFIELD, TRUSTEE, OF CLEVELAND, OHIO.

TELEPHONE-EXCHANGE SYSTEM.

1,249,583.

Specification of Letters Patent. Patented Dec. 11, 1917.

Application filed December 9, 1912. Serial No. 735,810.

To all whom it may concern:

Be it known that I, JOSEPH L. WRIGHT, a citizen of the United States, and resident of Cleveland, county of Cuyahoga, State of Ohio, have invented certain new and useful Improvements in Telephone-Exchange Systems, of which the following is a specification.

My invention relates to telephone-exchange systems and especially to that class known as semi-automatic. In systems of this class automatic switching mechanism is employed for effecting connections between calling and called subscribers. The switching mechanism is controlled by operators who are provided with suitable sending devices, or key-boards.

The general object of this invention is the improvement of the system mentioned. Some of these improvements may be stated as follows:

The method of calling or automatically picking out an idle trunk leading to a private branch exchange, or where subscribers have more than one telephone, listed under one number;

The method of trunking between exchanges wherein the switches are controlled entirely over two wires;

The method of registering or indicating the condition of traffic so as to show the number of trunks in use, and also the number of lines waiting to become connected to trunks;

Means controlled by the operator in case of false calls, or grounded lines, etc., so that such lines can be removed from the primary trunks and cleared back to the line equipment individual to the lines. This prevents tying up the trunking equipment. Only enough of this trunking equipment is ordinarily provided for taking care of the maximum number of connections.

In case of abnormal conditions when there are a large number of defective lines all of the primary trunks would become connected to such lines and prevent the legitimate calls receiving attention.

I have shown the various features applied to a semi-automatic system but it nat-

urally follows that they can be applied to a full automatic system.

My invention is illustrated in the accompanying drawings wherein:

Figure 1 shows a subscriber's line equipment, control circuit and meter device. 55

Fig. 2 shows a primary and first selector circuit.

Fig. 3 shows a second selector circuit.

Fig. 3^a shows a two-wire trunk for use 60 between exchanges.

Fig. 4 shows a connector circuit equipped for party line selective ringing.

Fig. 4^a shows a private branch exchange connector. 65

Fig. 5 shows the line and control circuits of the called subscriber.

Fig. 6 shows the key-set control circuit, the time element control device, and meter for registering the condition of the various 70 trunks.

Fig. 7 shows the circuit of the operator's key set switch and its associated shifting switch.

Fig. 8 shows an operator's key-board and 75 sending device.

Fig. 9 shows the arrangement of the various sheets when a subscriber calls for a line in the same exchange.

Fig. 10 shows the arrangement of the 80 sheets when a subscriber calls for a private branch exchange, or a subscriber who has more than one telephone.

Fig. 11 shows the arrangement of the 85 sheets when a subscriber calls for another subscriber in a different exchange.

Referring to Fig. 1, the subscriber's station at A is equipped with apparatus usual in common battery exchanges. The line wires from this station terminate at the central office in a line relay 2. The line relays are divided into groups, there being ten groups for each one hundred lines. Each group of ten line relays controls one group relay 3. This group relay when actuated 95 renders the row contact in the primary switch busy while the line relay when actuated makes the individual contact in this switch busy.

The switch W is common to a group of 100

one hundred lines and starts to rotate whenever a call originates and will continue to rotate until an idle primary switch is found.

- 5 12 is a relay controlled by the operator for removing the line relay 2, and the cut-off relay 1. When this relay 12 is energized, it locks itself through the subscriber's telephone, or in case of grounded or short-circuited lines, this relay will also remain energized. The action of this relay renders the line busy against other calls. When the line is cleared, or the circuit opened, relay 12 drops back and places the line and cut-off relays in condition to perform their regular functions.

Referring to Fig. 2 primary switch C for picking out the calling lines is shown. This switch first rotates and will continue to rotate until the row wiper 64 picks out the busy row contact. After this contact is reached the switch will cease rotating and step vertically until the individual busy test contact leading to the line relay 2 is found.

- 20 25 The first selector switch is shown at D, and responds to impulses from the sending device to rotate and then steps vertically to pick out an idle trunk leading to the second selector switch.

30 35 The wipers 63 of the switch C and wipers 56 of the switch D are joined as indicated by the heavy lines for conversational purposes. The tip and sleeve conductors are separated by the condensers 43 and 44. Relay 23 and the retardation coil connected respectively to the free and grounded side of battery supply talking current to the calling subscriber. 21 is the starting relay of the primary switch C, and corresponds to the line relay 2, (Fig. 1,) as it controls the action of the operator's key-set switch (Fig. 7). 22 is the row test relay, while 24 is the individual test relay. 25 is operated when the key-set switch picks out the trunk and re-

- 40 45 mains energized while the impulses are being transmitted. 27 is the test relay of the first selector D and remains energized while the test wipers 57 are passing over busy contacts. Relay 28 is energized whenever either 50 the rotary or vertical magnets of the switch C are operated, or when the vertical magnet of the switch D is operated. The circuits of these magnets are normally completed through the back contacts of relay 28, and 55 so, therefore, when it is actuated the magnet circuits are broken. The action set up between the relay and the magnets cause the latter to vibrate and step their respective switches.

60 65 The resistance coil 42 is placed in series with the rotary relay 29. This relay receives impulses from the sending device and operates magnet 34 causing the switch D to rotate. When the magnet 34 operates, it

closes its associated contact springs and places ground between the coil and the winding of relay 29. This action shunts out relay 29 and serves to regulate its action, or as soon as the magnet completes its stroke the relay which controls it is disabled. This arrangement avoids the necessity of fine adjustment between the repeating relay, the magnet and the sending device. This ground being placed to the winding at each impulse removes any static charge that may have accumulated on the impulse conductors.

Referring to Fig. 3, the second selector switch at E is operated first in a rotary direction to pick out the row, and then in a vertical direction to pick out the idle contact in the row. This switch is similar to the first selector switch shown at D and serves to pick out an idle connector switch. 81 is the repeating relay and is in series with the regulating coil 86. 82 is the interrupter relay corresponding to relay 28 (Fig. 2). 83 is the test relay, which is held energized while the test wipers of the switch E are passing over busy contacts.

Referring to Fig. 4, the connector switch G is provided with a set of wipers 390 which engage contacts leading to the tip and sleeve conductors of the called lines. The switch is also provided with a set of wipers 391 engaging contacts leading to the cut-off relays. This wiper also serves as a test wiper over which the condition of the called-for line is controlled. 305 and 310 are the repeating relays and respond to impulses from the operator's sending device. Each one of these relays is in series with an individual regulating resistance coil. 315 is a control relay and serves to remove the relay 325 and the retardation coil 335 from the wipers while the switch G is passing over busy contacts. 320 is the tip battery supply relay and is actuated when the called subscriber answers. 340 is the ringing relay operated by the commutator 370 when the wipers of the switch G engage contacts of the called-for line. This relay is cut off by the action of relay 330 which is controlled by relay 320 when the called subscriber answers. 345 is the busy test relay and is actuated when a busy line is found. Under these conditions, this relay locks itself to ground through the test wire 306. The action of this relay connects a suitable busy tone signal which is connected to the wire 341, back to the calling subscriber, notifying him that the called-for line is busy. The action of this relay closes the circuit of the release magnet 365 thereby restoring the switch G.

A controlling party-line selecting switch is shown at F. The contacts and wiper of the portion J cut on the generators 356, 357, 358 or 359 to either the tip or sleeve contacts

of the ringing relay 340. The contacts and wiper of the portion I serve to restore the selecting switch to its normal, or idle position at the proper time. The contacts and wiper of the portion H serve to connect ground to either the tip or sleeve contacts of the relay 340. When the portion J connects generator to the tip contact, the portion H connects ground to the sleeve contact and 10 when the portion J connects generator to the sleeve contact, the portion H connects ground to the tip contact. With this arrangement it is possible to ring subscribers' bells which are connected to either the tip 15 or sleeve side of the line to ground or if they are bridged directly across the tip and sleeve conductors.

The portion H of the switch also serves to release the connector switch G after the 20 called subscriber hangs up his receiver or when the calling subscriber hangs up, in case the called subscriber does not answer.

When the switch F is in its normal position, the wiper of the portion H rests on the 25 contact 334, the wiper of I on the contact 336, while the wiper of J, rests upon the contact 338.

A suitable ring-back tone test is connected to the wire 392 which in turn is connected to 30 the trunk back to the calling subscriber during each actuation of the ringing relay 340. This signal being connected in this manner notifies the calling subscriber that the party he called for is being rung.

35 The repeating relay 305 is regulated or controlled by the action of the vertical magnet of the switch G and also by the action of the stepping magnet 360 of the switch F. Relay 310 is controlled or regulated by the 40 action of the rotary magnet of the switch G.

Fig. 5 shows a subscriber's station at AA connected to the regular line equipment and as the circuits shown are identical to that of Fig. 1, they need not be described.

45 Referring to Fig. 6, the switch shown at Y corresponds to the switch W, (Fig. 1) and serves to pick out an idle secondary or key-set switch.

The switch X is a time element control 50 and comes into action when relays 130 and 132 have been held energized for an abnormal length of time. Relay 132 is energized as soon as an idle secondary switch is picked out, and should only remain energized long 55 enough for the secondary switch (Fig. 7) to pick out the tenth contact in the tenth row. The magnet 77 causes the switch X to step whenever the contact springs 36 are closed. These springs or contacts can be 60 controlled by any suitable timed circuit closer or the contacts can be located on the sending machine.

We will assume that relays 132 and 130 have been held energized beyond the time

necessary for the secondary switch to perform its proper functions: When the wiper α^2 reaches one of the contacts connected to the wire 139, the circuit of relay 78 is closed through the contacts of relay 132. The switch X continues to step at each closing of the contacts 36 and when the wiper α reaches one of the contacts to which the relay 76 is connected, then this relay is operated and performs the following functions: Ground is connected to wire 149 through the wiper 75 and contacts of the lower bank of the switch W, (Fig. 1) to wire 60, operating relay 29 (Fig. 2) thereby causing the switch D to take one step. Ground is also connected to wire 144 to the release magnet 166 of the 80 secondary switch M, thereby causing it to return to its normal position. The wires 18 and 148 are opened thereby disconnecting relays 5 and 21. The falling back of this latter relay disconnects relays 130 and 132 85 (Fig. 6) thereby unlocking relay 78 and no further action takes place.

If a calling subscriber is connected to the primary switch C and a faulty connection 90 takes place as just described, he can upon hanging up his receiver restore the switches C and D and originate another call.

The switch X performs no functions with 95 regular connections, unless the secondary switch and the primary trunk should become tied up, whereupon this switch comes into play and releases the apparatus.

Referring to Figs. 7 and 8, a secondary 100 switch, operator's key-board and sending device are shown. The switch M carries the wipers 167, 168, 169 and 162. This switch operates in the same manner as switch C (Fig. 2) as it rotates first to pick out the group in which the calling trunk is located, and then steps vertically to pick out the 105 trunk in the group. The wipers 167 are connected to the tip and sleeve side of the trunk and engage contacts leading to primary trunks over which the impulses are transmitted in order to operate the various selector and connector switches. 168 is the 110 row wiper and serves to pick out the group of ten in which the calling primary trunk is located. Relay 154 is connected to the individual test wiper and serves to pick out the particular trunk in the group calling.

Relay 156 is the signal relay and is placed in series with relay 25 (Fig. 2) when such a trunk is picked out. When relay 156 is energized, the circuits of the two lamps, 243 and 244 (Fig. 8) are closed and notifies the operator of a call. 152 is the starting relay and corresponds to relay 21 (Fig. 2) as it is energized as soon as the switch Y picks out the switch M. 153 is the row test relay operated when the row wiper engages an active contact. Relay 155 responds when the operator presses the answering button 115 120 125

248, thereby connecting her telephone set across the tip and sleeve conductors of the trunk. 157 is actuated when the operator presses the starting button 247. The action 5 of this relay disconnects relay 155 and connects the starting wire controlled by the cam 231 to the stepping magnet 161, thereby causing the wipers of the switch Z, shown at the portion N O and P, to rotate. The 10 stepping magnet 161 is operated once at each rotation of the sending device and connects the impulse wires from the key-board in their regular order. The order in which these impulses are transmitted is as follows: 15 At the first rotation of the sending device, impulses corresponding to the thousands are sent over the tip side of the trunk, and at the second rotation a single test impulse is sent over the sleeve side of the trunk. At the 20 third rotation impulses corresponding to the hundreds are sent over the tip side of the trunk and at the fourth rotation a single test impulse is sent over the sleeve side of the trunk. At the fifth rotation impulses to operate 25 the selective party line switch are sent over the tip side of the trunk and at the sixth rotation the tens impulses are sent over the sleeve side of the trunk. At the seventh rotation the units impulses are sent 30 over the tip side of the trunk and at the eighth a single test impulse is sent over the sleeve side of the trunk.

After all of these impulses have been delivered, then at the next rotation of the sending device, the wiper of the switch Z passing over the portion P closes the circuit of relay 158 which in turn causes the stepping magnet 161 to rapidly vibrate and cause the switch to rotate until it reaches its normal 40 position. Just before reaching this position, the circuit of the release magnet 166 of the switch M is energized thereby restoring the switch to its normal position.

Relay 163 corresponds to relay 28 (Fig. 45 2) and causes the magnets 164, 165 and 161 to vibrate and step their respective switches.

The operator's key-board shown in Fig. 8 consists of five rows of buttons, each row having ten buttons. Number one button of 50 each row is connected to a contact, operated by the cam 232. Number two button of each row is connected to a contact, operated by the cam 233. Corresponding buttons in each row are connected to the same contact. The 55 contact controlled by the cam 232 is closed just long enough to keep the relay 160, (Fig. 7) energized, while one impulse is being transmitted by the commutator 242. If number ten button is down, relay 160 would be closed by the cam 241, just long enough for ten impulses to be transmitted by the commutator 242.

The contacts of the commutator 242 are connected directly to a normally opened contact 60 of relay 160 and when this relay is

energized, impulses are connected to either the tip or sleeve side of the trunk, depending upon the position of the arm in regard to the contacts of the portion N.

The buttons, or keys, shown in the five rows R, S, T, U and V (Fig. 8) are of the usual locking and indicating type. When any one button of a certain row is pressed, it will release the button formerly pressed. The buttons 246, 247, 248, and 249 are of the non-locking type and the contacts controlled by them are only closed while the button is being pressed.

Referring to Fig. 3^a, the two-wire trunk selector, which in this instance is used as a second selector, is shown. The equipment shown to the left of the dot-dash line is located at one exchange, while the equipment shown to the right is located at another exchange. The trunk extending between the exchanges is composed of but two wires over which the impulses are transmitted and the release control exercised.

Relay 510 is slow acting and has its circuit closed by the action of relay 511. This latter relay becomes energized as soon as the trunk selector is picked out by the first selector. As soon as such a selection is made, ground is connected to the test wire thereby energizing relay 511, which in turn closes 95 the circuit of relay 510.

When the first selector switch is restored, ground is removed from the test wire and relay 511 falls back first, after which the slow relay 510 has its circuit opened. After relay 511 falls back, and before relay 510 breaks its contacts, ground is connected to the tip and sleeve conductors extending to the distant exchange and also to the test wire leading to the contacts in the banks of the first selector switches. Ground being placed on the tip and sleeve conductors at the same instant causes the release of the switch EE at the distant exchange. Ground being placed on the test contacts of the first selector switch renders the trunk busy for a sufficient length of time for the switch EE to restore.

Referring to the equipment shown to the right of the dot-dash line, the switch EE is provided with wipers which engage the tip and sleeve conductors leading to connector switches and also with a test wiper. This switch acts in the same manner as the first selector switch shown at D.

The two repeating relays 512 and 513 are connected respectively to the tip and sleeve conductors through the contacts of relays 502 and 503 and also through the contacts of relay 516. Relay 512 responds to the impulses from the sending device, and closes the circuit of the rotary magnet of the trunk selector EE while the action of relay 513 closes the circuit of the test relay 514. The action of the test relay closes the circuit of 125 130

the cut-off relay 515 preventing clicks or interference while the wipers of the switch EE are passing over busy trunks.

At the first rotation of the switch EE and 5 after relay 501 operates, the circuit of relay 516 is closed and maintained through the resistance coil 520. The wire joining the coil and the relay is connected to the test wiper of the trunk selector through the back contacts of the test relay 514.

At the first operation of relay 512 due to impulses from the sending device, the circuit of relay 500 is closed, which in turn completes the circuit of relay 502. The operation of this latter relay disconnects relay 512 from the tip conductor. Relay 502 has its circuit maintained and locked through the back contacts of relay 501. Relay 512, however, remains connected to the tip conductor of the trunk through the back contacts of relay 516, so that even though relay 502 is operated, relay 512 will remain connected to the tip conductor of the trunk, until after the operation of relay 516.

25 Relay 501 is operated by relay 513 which in turn operates relay 503 thereby partially disconnecting relay 513 from the sleeve conductor. Relay 513, however, is also connected to the sleeve conductor through the back contacts of relay 512. Relay 503 has its circuit maintained and locked through the back contacts of relay 512.

35 Relay 512 responding to the set of impulses, which is to operate the rotary magnet of the switch EE, remains connected to the tip conductor through the contacts of relay 516. Relay 513 responding to the test impulse for stepping the switch EE vertically, remains connected to the sleeve conductor while the impulse is being delivered.

40 Relay 513, however, completes the circuit of relay 501 which in turn operates relay 516. The operation of relay 516 opens one path to the tip and sleeve conductors 45 through which the relays 512 and 513 respectively are connected.

After all of the impulses for operating the switch EE have been delivered and the first impulse of the set to operate the connector also operates relay 512, the first impulse of the set to operate the connector in operating relay 512 causes it to at once become disconnected from the tip conductor as relay 516 is now operated. At the next 55 set of impulses sent over the sleeve side of the trunk to operate the connector, the relay 513 is at once disconnected.

From the foregoing it will be noted that 60 relays 512 and 513 only remain connected to the tip and sleeve conductors while the switch EE is being operated, but at the first impulse of the set belonging to the connector, they are at once disconnected.

When the called subscriber answers, 65 ground is connected to the test wire of the

connector switch with which the test wiper of the switch EE is in engagement. This ground shunts out relay 516, thereby placing the condensers in series with the tip and sleeve conductors of the switch EE. When 70 relay 516 is energized these condensers are short-circuited so the impulses can pass through and operate the connector switch.

Referring to Fig. 4^a the private branch exchange connector is similar to the regular connector shown in Fig. 4. The impulses are transmitted in the same manner and in the same order. The private branch exchange connector is reached through the regular first and second selector switches. The main difference between this switch and the regular connector switch is that when 80 the test relay 445 is operated instead of releasing the switch, it simply causes the circuit of the vertical magnet to be automatically interrupted. This action causes the switch to step vertically until the test wiper engages an idle trunk or line, whereupon the test relay falls back and the switch 85 comes to rest with its wipers engaging contacts leading to an idle trunk.

Relays 405 and 410 are the repeating relays which respond to impulses from the sending device. 415 is the control relay operated by relay 410 and serves to disconnect 95 relay 425 and the retardation coil 435 from the wipers, while the switch is passing over busy trunks. Relay 420 and retardation coil 435 are connected respectively to the free and grounded side of battery and thus furnish talking current to the called subscriber. 100 440 is the ringing relay which connects generator current of the frequency selected by the switch FF to the called line or trunk. Relay 425 is placed in series with the cut-off relay of the called line and when energized 105 serves to connect the tip relay 420 to the tip conductor and also to close the circuit of the ringing relay 440. 445 is the test relay operated by relay 405 when the test impulses are 110 transmitted. This test relay when operated closes the circuit of relay 410 which in turn closes the circuit of the vertical magnet of the switch GG, causing it to step vertically until the test relay is released. This relay 115 445 is released when the wiper 491 engages an idle contact and as soon as such a contact is found, relay 445 falls back, releases relay 410 which disconnects the vertical magnet causing the switch GG to come to rest with 120 its wipers resting on contacts of an idle trunk.

Lines appearing in the banks of the private branch exchange switch can also be multiplied into banks of the regular connector switches. With this arrangement any one of such lines can be called to predetermined numbers from the regular connectors, or the first idle one picked out through the private branch exchange connector. 125 130

With such a switch as shown in Fig. 4^a, more than one private branch exchange can be located in the same row of contacts. An exchange having but three trunks can be connected to the lower set of contacts in the bank. To call this exchange the last digit would end in "one." A blank contact will follow the third contact after which a second branch exchange can become connected to the remaining contacts. In order to call the second exchange, it will be necessary to have the last digit of a number end in "five."

The bank contacts can be split up or arranged in a manner to suit the number of trunk lines leading to private branch exchanges.

Under ordinary conditions there would be provided ten per cent. primary switches shown in Fig. 2 for serving a group of one hundred lines. These switches which first rotate in order to pick out a group of calling lines, is provided with a row test wiper which engages a set of row contacts. There is a separate row contact for each group of ten lines, and it therefore follows that for one hundred lines, there would be ten row contacts. Associated with each row contact there are ten individual test contacts. The primary switch C first picks out the group of ten lines through the medium of the row contact and then the individual line through the medium of one of the individual test contacts associated with the row contact. As soon as the switch C steps vertically, the row wiper moves with the switch spindle and leaves the row contact.

Each group of ten primary trunks shown in Fig. 2 has a control switch Y for picking out an idle secondary or key-set switch. The test wires connected to the contacts of the Y switch are multiplied to contacts in other Y switches, but the wire 141 leading from a bank of the Y switch is individual to a row contact in the key-set switch M and is not multiplied to contacts of other Y switches.

As soon as the switch Y picks out the switch M, ground is placed on the row contact of the selected M switch only, thus preventing interference in case other Y switches associated with other groups of trunks are searching for key-set switches M at the same time. In no case is ground placed on more than one row contact of any one key-set switch at the same instant. This method allows calls to come in from different groups of trunks at the same time, without interference.

In Fig. 1, the switch W, however, is individual to one hundred lines and serves a group of ten primary switches, or more, as the case may be. The row contacts of the primary switches of a particular group are multiplied.

The percentage and grouping of the various switches can be increased, or decreased,

to suit traffic conditions. The operators are provided preferably with three key-boards, each key-board having its individual switch M.

The cams on the sending device (Fig. 8) shown at 230 to 241, inclusive, may be common to a group of key-boards. The commutator 242, however, is preferably individual to one key-board or to one operator.

In the present instance I have shown the exchange, or exchanges, to be of ten thousand lines capacity and in case of a larger exchange, it would only be necessary to add additional selector switches and additional rows of buttons to the operator's key-board.

In describing the operation of my system, I will first trace a connection from a calling subscriber to another subscriber in the same exchange, using figures 1, 2, 3, 4, 5, 6, 7, and 8 arranged in accordance with Fig. 9.

The subscriber at A removing his receiver closes the circuit of the line relay which in turn closes the circuit of the group relay 3. This latter relay operating closes the circuit of relay 4 which in turn connects ground to one terminal of relay 5 and also closes the circuit of the stepping magnet 7. The stepping magnet 7 operating closes the circuit of relay 6 which in turn opens the circuit of the magnet causing it to vibrate and step around the wipers of the switch W. This switch will continue to rotate until an idle primary switch such as shown at C (Fig. 2) is found. As soon as such an idle switch is found, relay 5 is placed in series with relay 21 (Fig. 2) as follows: Ground, contacts of relay 4, 5, 18, contacts of relay 76 (Fig. 6) 148, upper bank of switch W, 19, 21, 70, contacts of relay 24, to battery B. Relay 5 becoming energized opens the circuit of the stepping magnet 7 bringing the switch W to rest. Relay 21 operating, closes the circuit of the rotary stepping magnet 31 by the following path: Battery B, 80, back contact of relay 24, 71, contacts of relay 28, back contacts of relay 22, 31, to ground. The operation of magnet 31, causes the primary switch C to rotate until the wiper 64 reaches a busy contact to which is connected wire 13, leading to the contact of relay 3.

As soon as the row contact is found, the circuit of relay 22 is closed as follows: Battery B, 80, contacts of relay 24, 71, 22, 64, 13, contacts of relay 3 to ground. Relay 22 operating disconnects rotary magnet 31 and in its place connects the vertical magnet 30, thereby causing the switch C to step vertically until the busy individual test contact is found. As soon as this contact is reached, the circuit of relay 24 is closed as follows: Battery B, 24, 68, 67, 11, contacts of relay 2, to ground, through the contacts of relay 1. Relay 24 operating opens the wire 71 disconnecting relay 22 which, in falling back disconnects relay 24 from the wire 67.

and connects it instead to wire 66. Relay 24 is now placed in series with relay 1 and the operating of this latter relay disconnects the line relay 2, which in turn disconnects the 5 group relay 3. The operating of relay 24 connects battery to the windings of relays 23 and 25. The falling back of relay 22 connects ground to the retardation coil 26. Battery is supplied through this coil and 10 relay 23 to the calling subscriber for talking purposes.

Relay 21 remains energized until the primary switch C finds the calling line and until the key-set switch M finds the calling 15 trunk. Relay 21 when first actuated connects battery to the relay 130 over the wire 79 and also connects battery to the individual test contact of the switch M over the wire 62.

20 Relay 130 operating closes the circuit of the stepping magnet 133 of the switch Y. This magnet operating closes the circuit of the interrupter relay 134, which causes a vibrating effect between the magnet and the 25 relay, and the switch will continue to rotate until an idle key-set switch is found. When such a switch is found as shown in Fig. 7, relay 131 is placed in series with relay 152 (Fig. 7) by the following path: 30 Ground, contacts of relay 130, 131, 138, bank contacts of Y, 140, 152, 195, cam springs 196, 197, to battery B through the operator's jack 400.

Relay 131 operating connects battery to 35 relay 132 causing it to operate. The operation of this latter relay places ground on wire 138 thereby shunting relay 131. This direct ground placed on the wire 140, which is multiplied to other Y switches, renders 40 the selected key-set switch M busy against other calls. The operating of relay 132 also connects ground to the row contact of the key-set switch M by the following path: Ground, 139, bank contacts of Y, 141, to row 45 contact, (Fig. 7). Relay 152 operating connects ground to the rotary magnet 165, through the back contact of relay 163 thereby causing the switch M to rotate. This switch will continue to rotate until the row 50 contact is found, whereupon the circuit of relay 153 is closed by the following path: Battery B, contacts of relay 152, 176, 153, 171, 168, 141, 139, contacts of relay 132 to ground.

55 The action of the key-set switch M is identical with that of the primary switch C.

The operating of relay 153 disconnects the rotary magnet 165 and in its place connects the vertical magnet 164 thereby causing the 60 switch M to step vertically until the busy individual test contact is found. As soon as this contact is found the circuit of relay 154 is closed as follows: Ground, 154, 172, 65 62, 80, contacts of relay 21 to battery B. The operating of relay 154 disconnects relay

152, thereby cutting off the magnets and causing the switch M to come to rest with its wipers engaging contacts leading to the calling primary trunk, (Fig. 2). Relay 152 becoming disconnected opens the circuit of relay 153 and this latter relay in falling back places relays 156, and 25 in series by the following path: Ground, back contacts of relay 153, 175 back contacts of relay 157, 202, contacts of relay 155, 156, 193 contacts 75 of relay 158, 170, 169, 59, 25, to battery B, through the contacts of relay 24. The operating of relay 25 disconnects relays 21 and 5. The releasing of the latter relay frees the switch W, placing it in condition 80 to pick out other primary switches.

Relay 156 operating connects battery to wire 181, 183, thereby lighting the two lamps 243 and 244, (Fig. 8). As soon as relay 21 (Fig. 2) became disconnected, battery was removed from the individual test contact of the switch M, thereby allowing 85 relay 154 to fall back. The falling back of relay 21 also opens the circuit of relay 130 which in turn opens the circuit of relay 132 90 and allows the switch Y to be used by other trunks in picking out other key-set switches.

The lighting of the two lamps 243 and 244 notifies the operator of a call and she then presses button 248 which operates relay 155. The operation of this relay connects her telephone set across the tip and sleeve conductors of the trunk. The action of this relay also disconnects relay 156 extinguishing lamps 243 and 244, but causing 100 the lamp 245 to remain lighted. Relay 156 becoming disconnected allows relay 25 (Fig. 2) to fall back closing the tip and sleeve conductors of the primary trunk and allowing the operator to converse with the calling 105 subscriber.

The operator after getting the proper number from the subscriber, presses one button in each row corresponding to the number desired, and then presses the starting 110 button 247, which closes the circuit of relay 157 by the following path: Ground, 247, 186, 157, 193, 170, 169, 59, 25, to battery B, through the contacts of relay 24. Relay 25 again operating opens the trunk conductors 115 to prevent the calling subscriber hearing the impulses.

The operating of relay 157 disconnects relay 155, extinguishes lamp 245, and causes the guard lamp 244 to light. The action of 120 relay 157 also connects the starting wire 189, connected to the contacts operated by the cam 231, to the stepping magnet 161. As soon as the cam contacts are operated the wipers of the shifting switch Z take one step, and connect the impulse wire 191 to the tip side of the trunk 150 through the contacts of relay 160 and the portion N of the switch Z.

If number nine button in the row R is 125 pressed, relay 160 will be held energized by 130

the operation of cam 240 until nine impulses have been transmitted by the commutator 242.

These impulses operate the rotary relay 29 (Fig. 2) by the following path: Ground, 242, 191, 190, 192, contacts of relay 160, N, 150, 167, 60, 54, 29, 42, cam springs 40 to battery B. Relay 29 responding to these impulses closes the circuit of the rotary magnet 34, causing the switch D to rotate and bring its wipers in line with a group of contacts in the ninth row.

As soon as the springs operated by the rotary magnet 34 are closed, ground is at once placed between the winding of relay 29 and the coil 42, thereby shunting out relay 29. This relay in falling back removes battery from the winding of magnet 34 itself. It will be noted from the foregoing that if the impulses from the sending device had been a trifle longer, relay 29 would be shunted out, just as soon as the magnet 34 completes its stroke.

Ground being connected in this manner after each impulse serves to dissipate any static charge which may have accumulated on the impulse conductors.

After the rotary impulses have been sent the starting cam 231 causes the switch Z to take another step, thereby connecting the impulse wire to the sleeve side of the trunk 151. Relay 160 is now held energized by the action of cam 230 until a single impulse is transmitted. This impulse operates the relay 27, (Fig. 2) by the following path: Ground, 242, 191, 190, 192, contacts of relay 160, 198, N, 151, 167, 61, relay 27, cam springs 40 to battery B.

Relay 27 is operated upon receiving this impulse and is held energized thereafter by the following path: Battery B, contacts of relay 25, contacts of relay 27, 58, contacts of relay 28, 72, 32, 75 cam springs 41 to ground. The cam springs 41 were operated when the switch D took its first rotary step. The operating of relay 27 closes the circuit of vertical magnet 33 by the following path: Battery B, contacts of relay 28, 71, contacts of relay 27, 33 to ground. Magnet 33 in operating closes the circuit of relay 28, which in turn opens the circuit of the magnet 33 itself. The action of this relay and magnet causes a vibrating effect and the switch D steps vertically. When the circuit of relay 28 is closed by the action of magnet 33, the circuit of relay 27 itself is partially opened, but it will remain energized by the test wiper 57 engaging ground or busy test contacts. While the relay 28 is operated and the wiper 57 comes to rest on an idle contact, then relay 27 will at once become deenergized and disconnect the vertical magnet 33, causing the switch D to bring its wipers to rest on contacts leading to an idle second selector.

The controlling of the test relay 27 in the manner described insures a full step of the switch as the wiper 57 fully engages a test contact before relay 27 is opened by the action of relay 28.

As soon as the switch D takes its first vertical step, or while in the act of taking this step, the cam springs 40 are opened, thereby disconnecting relays 27 and 29 respectively from the tip and sleeve conductors of the trunk.

At the third rotation of the sending device, impulses corresponding to the hundreds are sent over the tip side of the trunk corresponding to the button pressed in the row S. These impulses operate relay 81 of the second selector switch E (Fig. 3). This relay is connected to the tip side of the trunk 90 through the cam springs 88. The action of relay 81 closes the circuit of the rotary magnet 85 causing the switch E to rotate and bring its wipers in line with contacts leading to connector switches.

At the fourth rotation of the sending device, a single test impulse is sent over the sleeve side of the trunk operating relay 83. This relay in acting closes the circuit of the vertical magnet 84, causing the switch E to step vertically until the test wiper 102 engages contacts leading to an idle connector switch.

The test relay 83 is controlled in the same manner as the test relay 27 (Fig. 2) and the rotary relay 81 and the rotary magnet are controlled and regulated in the same manner as the rotary and vertical magnets of the switch D.

The action of relay 305 completes the circuit of the shifting relay 330 as follows: Ground, from the test wire 306, contacts of relay 305, 317, winding of relay 330, 318 to battery B, from the back contacts of relay 320.

At the first vertical step of the switch E, the cam springs 88 are opened, thereby disconnecting relays 81 and 83 respectively from the tip and sleeve sides of the trunk.

At the fifth rotation of the sending device, impulses corresponding to the button pressed in the row V, (Fig. 8) are sent over the tip side of the trunk operating relay 310 of the connector switch G (Fig. 4). The action of this relay closes the circuit of the stepping magnet 360 of the party line distributing switch by the following path: Ground, contacts of relay 310 321, contacts of relay 330, 323, 360, 318, contacts of relay 320 to battery B. The switch F takes a number of steps corresponding to the impulses delivered. In the present instance, I have shown generator 356 connected to the first two contacts in the bank J so that if either one or two impulses are transmitted, this same generator will become connected to the sleeve contact in the ringing relay.

If six or seven impulses are transmitted the same generator will be connected to the tip contact of the ringing relay. The contacts are arranged in this manner because one of the party line frequencies is also used for straight or independent line ringing. We will assume that five impulses have been transmitted, then generator 359 will become connected through the fifth contact in the bank J to the sleeve contact in the ringing relay 340. Ground is also connected from the portion H to the tip contact of the ringing relay 340. The action of relay 310 also closes the circuit of relay 315 by the following path: Battery B, 319, 315, contacts of relay 305, 306, 102, (Fig. 3), 89, contacts of relay 82 to ground.

At the sixth rotation of the sending device, impulses corresponding to the button pressed in the row T are sent over the sleeve side of the trunk operating relay 305. This relay operating unlocks relay 315 and closes the circuit of the rotary magnet 355 by the following path: Battery B, contacts of relay 305, 314, cam springs 380, 316, 355, to ground. The operation of the rotary magnet causes the connector switch G to rotate and bring its wipers in line with a group of contacts containing terminals of the desired line.

At the seventh rotation of the sending device, impulses corresponding to the button pressed in the row U are sent over the tip side of the trunk operating relay 310 again. The operation of this relay closes the circuit of the vertical magnet 350 causing the switch G to step vertically and bring its wipers into engagement with contacts of the desired line. The action of relay 310 again energizes relay 315, preventing interruption while the wipers are passing over busy contacts. When the switch G takes its first vertical step, the cam springs 380 operate and disconnect the rotary magnet 355.

At the eighth rotation of the sending device, a single test impulse is sent over the sleeve side of the trunk, operating relay 305 again. This relay now operating connects the test relay 345 directly to the test wiper 391. If the called line is busy, this relay 345 will become energized and lock itself to ground through the test wire 306. The action of this relay connects ground to the release magnet 365 thereby operating it and causing the switch G to restore. The action of this relay also connects a busy tone from the wire 341 to the trunk 301 notifying the calling subscriber that the called-for line is busy.

In case the line is not busy relay 345 will not be effected. Relay 305 in acting again unlocks relay 315, which, falling back places the relay 325 in series with the cut-off relay of the called line by the following path: Battery B, contacts of relay 315, 312, 325, 311, contacts of relay 305, 308, 391, 107, cut-

off relay to ground. The action of the cut-off relay disconnects the line relay and the action of relay 325 closes the sleeve side of the trunk and disconnects the repeating relay 310. This relay also connects battery to the winding of the tip relay 320 and also closes the circuit of the ringing relay 340 by the following path: Ground commutator 370, 340, 326, contacts of relay 325, 324, contacts of relays 330 and 315, contact of relay 330, 322, vertical magnet 350 to battery B. The vertical magnet 350 does not operate in series with the winding of the ringing relay 340. The action of this ringing relay connects generator 359 to the sleeve conductor 304 and connects ground to the tip conductor 302, thus ringing the subscriber's bell AA at intervals. At each actuation of relay 340 a suitable ring-back test is sent over the sleeve side of the trunk notifying the calling subscriber that the called-for party is being rung.

At the next rotation of the sending device, relay 158, (Fig. 7) is connected to battery through the bank P of the switch Z. The action of this relay connects ground to the magnet 161 and also unlocks relay 157. Magnet 161 will vibrate rapidly and cause the switch Z to rotate until the wipers reach their normal position. Just before reaching this position the wiper of the portion P connects relay 158 in series with release magnet 166. The action of the release magnet causes the switch M to restore. This switch restoring disconnects the operator's key-set from the primary trunk and renders it available for other calls.

When the called subscriber removes his receiver during the non-ringing interval, and causes relay 320 to become energized, the action of this relay unlocks relay 330 and disconnects relay 305, closing the tip side of the trunk. The falling back of relay 330 disconnects the ringing relay 340.

The calling and called subscribers are now able to converse without interference, and the talking circuit throughout the various figures is indicated by the heavy lines.

When the called subscriber hangs up his receiver, relay 320 falls back after which the circuit of the magnet 360 is closed by the following path: Ground, commutator 353, I, 398, contacts of relay 330, contacts of relay 315, 321, contacts of relay 330, 323, 360, 318 to battery B, through the contacts of relay 320. Magnet 360 will continue to vibrate until the wiper of the portion I rests on the contact 336. Just before this contact is reached, the wiper at H closes the circuit of the release magnet 365 by the following path: Battery B, 365, 332, H, 327, to ground through the contacts of relay 315. The action of the magnet 365 restores switch G to its normal position.

The calling subscriber hanging up his re-

ceiver causes the relay 23 (Fig. 2) to fall back thereby closing the circuit of the release magnet 32 by the following path: Battery B, cam springs 38, 73, contacts of relay 23, 58, contacts of relay 28, 72, 32, cam springs 41 to ground. The circuit of the release magnet 35 is also closed in the same manner. Magnet 32 operating causes the release of the primary switch C and the operation of magnet 35 causes the release of the first selector switch D.

As soon as the wipers of the switch D leave the contacts of the second selector switch (Fig. 3) relay 683 falls back and closes the circuit of the release magnet 93 of the switch E. The operation of this magnet causes the second selector switch to return to its normal position.

In case the called-for party does not answer, then the calling subscriber also releases the connector switch. This release is brought about as follows: When the second selector switch (Fig. 3) restores ground is removed from the test wire 306, thereby unlocking relay 330, just as though relay 320 were energized. Relay 330 falling back and relay 320 being in its normal position allows the circuit of the magnet 360 to be closed by the same path as formerly traced, thereby restoring all parts of the connector switch to its normal position.

In case of short-circuited or grounded lines which would originate calls so as to connect effective lines to the operator's key-board, they would be handled in the following manner: Such calls would become connected to the operator's key-board in the regular manner and the operator pressing her answering button and failing to receive a response would immediately depress button 249, thereby closing the circuit of relay 12 by the following path: Ground, 249, 250, 162, 670, 37, 15, 12 to battery B. The operation of relay 12 disconnects ground from the cut-off relay 1 and battery from the line relay 2. Relay 1 will immediately fall back and relay 12 will remain locked to ground in case the line is grounded, or in case of a shortcircuited line would be locked to ground through the back contacts of relay 1. The operation of relay 12 connects battery to one terminal of relay 1 through a suitable resistance coil 671 so as to render this line busy against calls through the connector switches. The action of relay 12 also lights a suitable signal lamp 17 to notify the attendant that the line is out of order.

The operator pressing button 249 also closes the circuit of relay 159, (Fig. 7). The operation of relay 159 allows relay 157 also to have its circuit closed from ground through the button 249. The operation of button 249, therefore closes the circuits of relay 159 and 157. Relay 157 connects the wire leading to the starting cam on the send-

ing machine to the stepping magnet 161 in the regular manner, causing the switch Z to start stepping. The operation of relay 159 removes battery from the first two contacts of the portion P of the switch Z but connects battery to the next series of contacts following. With this arrangement the circuit of relay 158 is completed after the switch Z takes two steps. As soon as the switch Z, however, takes one step, impulses are transmitted to the first selector D the impulses being controlled by which ever key happens to be depressed in the row R. These impulses, or at least the first impulse operates the rotary relay of the switch D, causing it to step and complete the circuits of the release magnets 32 and 35, thereby allowing the first selector D and the primary selector C to restore.

Either the restoring of the switch C, or the disconnecting of the cut-off relay 1 by the action of relay 12, allows relay 24 (Fig. 2) to fall back, thereby removing battery from the winding of relay 25. Relay 157, however, in series with relay 25, also becomes deenergized as well as relay 159. These two latter relays falling back connect battery to the first two contacts of the portion P, thereby at once completing the circuit of relay 158, causing the switch Z to rotate to its normal position and restore the switch M.

In case of trunk calls, wherein lines or trunks leading to a manual switch-board are connected directly to the bank contacts of the first selector switch D, then the operator depresses button 246. The operation of this button completes the circuits of relay 159 and 157 and after the first selector D receives the rotary impulses and the vertical test impulses, the switch M is caused to restore by the action of the switch Z in rotating after taking two steps.

By placing grounded, short-circuited lines, etc., under control of the operator such lines can be at once disconnected from the primary trunks. Under ordinary conditions only ten per cent. of these trunks would be used, and in case of a larger number of lines in trouble in one group all the primary trunks would become tied up.

It will be noted that relay 12 has its circuit maintained or locked either through a grounded line, or a short-circuited line, and it therefore follows that as soon as the ground or short-circuit is removed that relay 12 will fall back and place relays 1 and 2 in operative condition.

In case of annoying subscribers, the relay 12 can be made very sluggish or slow-acting so that when the operator presses the button 249 the subscriber can not become connected to a primary switch, nor originate a call by operating his receiver hook, unless he does it very slowly.

If the relay 12 is sluggish it will naturally not drop back in case the subscriber should rapidly operate his switch hook. An impatient subscriber under ordinary circumstances would rapidly operate his switch hook and in such an event relay 12 would remain energized when made sluggish. If the line circuit is, however, held open for a certain time interval the regular line equipment is reconnected.

10 I will now trace a connection from a subscriber desiring to converse with another subscriber in a private branch exchange or with a subscriber who has more than one 15 telephone line under one number, and arrange the various circuits as shown in Fig. 10.

The calling subscriber removing his receiver is connected to the key-board in the 20 manner previously described in connection with Fig. 9.

The operator upon getting the call sets up the proper number on her key-board and presses the starting button 247 causing the 25 impulses to be transmitted in the regular manner. The first selector D is first operated, then the second selector E. The operation of this latter switch causes an idle private branch connector to be selected. After 30 this selection is completed, the impulses are first sent over the tip side of the trunk operating relay 410. The operation of this relay closes the circuit of relay 415 and also closes the circuit of the stepping magnet 460 of the 35 switch FF causing the generator current of the proper frequency to be selected.

The next set of impulses are transmitted over the sleeve side of the trunk, operating relay 405, which unlocks relay 415 and closes 40 the circuit of relay 430. The action of relay 405 also completes the circuit of the rotary magnet of the switch GG, thereby causing the same to rotate and bring its wipers in line with a row of contacts leading to a private 45 branch exchange or exchanges.

The next set of impulses are transmitted over the tip conductor and operate relay 410. This relay now closes the circuit of the vertical magnet 450 and causes the wipers of 50 the switch GG to engage contacts of the first trunk leading to the private branch exchange. The operation of relay 410 again closes the circuit of relay 415 which prevents interference while the wipers engage 55 contacts and before the test impulse has been transmitted.

The operation of relay 415 removes ground from the winding of coil 435 and battery from the winding of relay 425. The 60 coil 435 is normally connected to the tip side of the trunk and relay 425 is normally connected to the test wiper 491. The operation of relay 415 thereby prevents the operation of the cut-off relays of the various lines as 65 the test wiper 491 engages their terminals.

The test impulse is transmitted over the sleeve side of the trunk operating relay 405. The operation of this relay at this period connects the test relay 445 to the test wiper 491. If the first trunk or line is busy then the test relay will become energized and close the circuit of relay 410. The operation of this latter relay connects ground to the vertical magnet 450 causing the switch GG to step vertically until an idle trunk is found. 70 When such a trunk is found relay 445 falls back and the switch GG comes to rest with its wipers engaging contacts of an idle trunk. When the relay 445 is energized, ground is connected to the winding of relay 410 which in turn closes the circuit of the vertical magnet 450. The operation of the vertical magnet closes its associated contact springs, thereby shunting out relay 410 which is in series with a regulating or resistance coil 800. As soon as relay 410 is shunted out, it, of course, follows that the circuit of the vertical magnet itself is broken and as soon as the magnet circuit is broken then the set of contact springs are opened, removing the shunt from relay 410 thereby allowing it to become energized again. This action will cause the magnet 450 to vibrate and operate the switch GG in a vertical direction. 85 As soon as the circuit of relay 445 is broken, the circuit of relay 410 is broken, which in turn opens the circuit of the vertical magnet 450. As soon as an idle trunk is found, relay 445 falls back and allows relay 425 to be placed in series with the cut-off relay of the called line. The action of relay 425 90 closes the sleeve conductor, removes relay 410 and completes the circuit of the ringing relay 440. The action of relay 425 connects battery to the winding of the tip relay 420. The action of relay 440 connects generator current of the frequency selected by the switch FF to the called line or trunk. 95

When the called subscriber answers relay 420 is energized unlocking relay 430, which 100 in turn opens the circuit of the ringing relay 440. 105

In case all of the trunks leading to an exchange are busy, then the switch GG will step vertically until a blank set of contacts is reached; that is to say, one to which no trunks are connected. To these blank contacts, however, is connected a suitable busy tone signal which notifies the calling subscriber that all the trunks are engaged. 115

The contact of the blank set which the wiper 491 engages is connected to ground through suitable resistance coil so as to energize relay 425. This coil takes the place of the cut-off relay. 120

When the called subscriber hangs up his receiver, the circuit of the stepping magnet 460 of the switch FF is closed, thereby causing the wipers to rotate until they reach their normal position. 125

The calling subscriber hanging up his receiver, releases the primary, first and second selector switches in the regular manner.

In tracing a call from a subscriber in one exchange to a subscriber located in another exchange, figures 1, 2, 3^a, 4, 5, 6, 7 and 8 are used, arranged in accordance with Fig. 11.

The calling subscriber is connected to the key-board in the regular manner and the operator upon receiving the signals and learning the number desired, presses the buttons on the key-board corresponding to that number and presses starting button 247. The impulses operate the first selector switch in the regular manner, causing its wipers to engage contacts leading to an idle trunk selector, such as shown in Fig. 3^a.

As soon as the trunk selector is picked out by the first selector switch D, ground is connected to the test contact, thereby closing the circuit of relay 511 through the back contacts of relay 510. As soon as relay 511 becomes energized it locks itself to ground over the test wire, and at the same time closes the circuit of relay 510 holding it energized until after the first selector switch D restores. After the trunk selector is picked out, impulses are transmitted over the tip conductor operating relay 512 which in turn closes the circuit of the rotary magnet 518 by the following path: Ground, contacts of relay 512, 573, cam springs, 561, magnet 518, to battery B. The operation of the rotary magnet causes the switch EE to rotate and bring its wipers in line with contacts leading to connector switches. The operation of relay 512 also closes the circuit of relay 500 by the following path: Ground, contacts of relay 512, 573, 500 to battery B. The operation of relay 500 closes the circuit of relay 502 by the following path: Ground, back contacts of relay 501, 574, contacts of relay 500, 568, 502, 542, cam springs 560 to battery B. The cam springs 560 are closed at the first rotary motion of the switch EE. Relay 502 when operated has its circuit maintained through the back contacts of relay 501.

The test impulse is transmitted over the sleeve side of the trunk operating relay 513. The operation of this relay closes the circuit of relay 501 by the following path: Ground, back contacts of relay 512, 536, 569, contacts of relay 513, 538, 501 to battery B. The operation of relay 501 closes the circuit of relay 503 by the following path: Ground, back contact of relay 512, 536, 569, contacts of relay 501, 570, 503, 542 cam springs 560 to battery B. After relay 503 is operated its circuit is maintained through the back contact of relay 512. The operation of relay 501 also completes the circuit of relay 516, which has its circuit maintained, or locked, through the resistance coil 520, to battery B, through the cam springs 560. The oper-

ation of relay 516 short-circuits the condensers 566 and 567.

The operation of relay 513 closes the circuit of the test relay 514 by the following path: Ground, back contacts of relay 512, 536, 569, contacts of relay 513, 538, 563, cam springs 561, 543, 514, to battery B. The operation of the test relay closes the circuit of relay 515 and also closes the circuit of the vertical magnet 519 by the following path: Ground, contacts of relay 514, 540, contacts of relay 512 contacts of relay 517, 519, to battery B. The operation of the magnet 519 causes the switch EE to step vertically until an idle connector switch is found. The operation of relay 515 severs the tip and sleeve conductors while the wipers of the switch EE are passing over busy contacts. The circuit of relay 514 is maintained through the back contacts of relay 517 and also to ground by the test wiper engaging busy contacts. When an idle contact is found, the relay 517 is energized, then relay 514 falls back, disconnects the vertical magnet and causes the wiper of the switch EE to rest on contacts leading to an idle connector switch. Relay 514 falling back disconnects relay 515 which thereupon closes the tip and sleeve conductors. Relay 516, however, remains energized in series with the resistance coil 520. The operation of this relay short-circuits the condensers so as to allow impulses to pass through to the connector switch.

At the first impulse sent over the sleeve conductor operating relay 513 causes relay 502 to have its circuit opened due to the operation of relay 501.

The next set of impulses are sent over the tip conductor and operate the magnet 360 of the switch F (Fig. 4). The first impulse of this set operates relay 512, through the back contacts of relay 502. The operation of relay 512 closes the circuit of relay 500 which in turn closes the circuit of relay 502, and the operation of this latter relay disconnects relay 512 from the tip conductor 530. Relay 512 is now disconnected from the tip conductor while the balance of the impulses belonging to a set to operate the connector, are being transmitted.

It will be seen from the foregoing arrangement that the first impulse sent over the tip conductor 530, the repeating relay 512 is at once disconnected from the conductor to prevent interference while impulses are being transmitted to operate the connector switch.

The next set of impulses to operate the rotary magnet of the connector are sent over the sleeve conductor 531. The first impulse closes the circuit of relay 513, through the back contacts of relay 503. The operation of relay 513 closes the circuit of relay 501 which in turn closes the circuit of relay 503.

The action of the latter relay disconnects relay 513 from the sleeve conductor 531. The repeating relay at the first impulse is disconnected from the sleeve conductor as 5 relay 516 remains energized. The operation of relay 501, however, unlocks relay 502, thereby again connecting relay 512 to the tip conductor 530.

The next set of impulses to operate the 10 vertical magnet of the connector are sent over the tip conductor. The first impulse of this set operates relay 512 and this relay is again disconnected from the tip conductor 530. The operation of relay 512, however, 15 disconnects relay 503, thereby allowing relay 513 to be again connected to the sleeve conductor 531.

The test impulse for the connector is next sent over the sleeve conductor which operates 20 relay 513 as before, but the operation of this relay closes the circuit of relay 501 which in turn closes the circuit of relay 503, thereby disconnecting relay 513 from the sleeve conductor. Relay 512, is, however, 25 again connected to the tip conductor 530 when relay 501 operating unlocks relay 502.

After the test impulse has been transmitted the entire connection is established and the sending device and key-set switch 30 are disconnected from the talking circuit and the calling subscriber at one exchange connected as indicated by the heavy lines to the called subscriber's line at the distant exchange.

35 When the called subscriber answers, ground is connected to the test wire through the back contacts of relay 330, and the rotary cam springs of the switch G. This ground is connected to the same terminal of 40 the resistance coil 520 to which the relay 516 has its locking contact connected, and it is, therefore, at once shunted. Relay 516 falling back removes the short-circuit from the condensers 566 and 567.

45 As soon as relay 516 falls back the relays 512 and 513 are furnished with an additional path to the tip and sleeve conductors 530 and 531 respectively.

When the called subscriber hangs up his 50 receiver, the connector is released in the manner previously described.

When the calling subscriber hangs up his receiver, the primary and first selector switches are also released in the manner 55 previously described.

When the first selector switch wipers leave the contacts of the trunk selector, ground is removed from the test wire, thereby opening the circuit of relay 511. This relay is 60 quick acting and immediately falls back and connects ground to the tip and sleeve conductors 530 and 531, and also to the test wire through the back contacts of relay 510. Relay 510 being slow acting falls back after 65 a suitable time interval, and removes ground

from the tip and sleeve conductors, and also from the test wire.

Ground being connected to both conductors at the same time operates relays 512 and 513 at the same instant, thereby closing the 70 circuit of relay 515 which severs the tip and sleeve conductors and at the same time closes the circuit of the release magnet 520 restoring the switch EE to its normal position. 75

In case the subscriber at one exchange calls for a subscriber located in the private branch exchange at a distance point, then the private branch connector (Fig. 4^a) is reached through the trunk selector (Fig. 3^a). 80 The impulses are transmitted in the regular order just as though the call was for a subscriber at a distant exchange. The private branch connector (Fig. 4^a) is operated in the same manner previously described, and 85 when the called subscriber answers, ground is connected to a test wire 406 by the following path: Ground, back contacts of relay 415, portion HH of the switch FF, back contacts of relay 430, to 406. This ground 90 shunts out relay 516 (Fig. 3^a), thereby placing the condensers 566 and 567 respectively from the tip and sleeve conductors. Ground being connected to the test wire 406 shunts out relay 516 as follows: Test wire 406, 95 wiper 565, 544, back contacts of relay 514, 534, locking contacts of relay 516 to the winding thereof. As the other terminal of this relay is connected to ground it therefore follows that this relay is shunted. 100

In connection with Fig. 4^a, however, a special provision is made whereby when the final test impulse is transmitted, operating relay 405, a momentary ground is at once connected to the wire 406 through the cam 105 springs 480. This momentary ground will shunt relay 516, and thereby insert condensers 566 and 567 into the talking circuit even before the called subscriber removes his receiver. 110

The private branch connector (Fig. 4^a) can be provided with the same ringing arrangement in connection with the switch FF as shown in Fig. 4 so as to provide ringing from either the tip or sleeve side of the line 115 to ground.

It will be noted that the regular repeating relay and regulating resistance coil are utilized for causing the automatic stepping of the private branch exchange connector. The 120 same result would be obtained with the regular selector and connector switches shown if ground were connected to the windings of their repeating relays and maintained long enough to allow their respective magnets 125 to shunt these relays. In the private branch exchange connector this ground is maintained by the action of the test relay. With this arrangement therefore it is possible to cause the special connector to step vertically 130

by predetermined impulses from the sending device and so pick out a particular trunk or line as well as to automatically pick out the first idle one.

- 5 Referring to Fig. 1, the metering or registering device K, can be located before a special operator. This meter is for the purpose of registering the number of calling lines, waiting to be picked out by primary switch 10 C. The scale of this meter can be calibrated in any desired manner, for instance when a single line relay 2 is energized enough current will flow through the resistance coil 20 in series with relay 3 to register one point, 15 thus indicating that only one relay is energized.

I have shown this meter in connection with an external shunt 16. The meter, however, can be of the direct reading type, and 20 placed in series with the winding of relay 3.

Each group relay 3, one of each which serves ten lines, can have its winding connected to battery through the shunt 16, so that one meter can serve or register a large 25 number of lines. The winding of relay 3 is of a low resistance in comparison with the resistance coil 20. This difference in resistance will be necessary for there may be several line relays 2 in the same group energized, and current will flow through several 30 multiple paths through the relay 3.

Referring to Fig. 6 a separate meter is shown at K¹. This meter registers, or indicates the number of primary trunks in Fig. 35 2, which are waiting to become connected to key-boards through secondary switches M.

Relay 21 (Fig. 2) remains energized until the primary trunk is picked out by secondary switch M. As soon as the trunk is picked 40 out relay 21 falls back. In the present instance I have shown a meter K¹ in connection with shunt 616 which is in series with the windings of relays 130. These relays are energized through resistance coils 39 45 when the relays 21 are operated.

This meter K¹ is calibrated so as to register for, or indicate each relay 21 held energized.

By means of these meters the chief operator, or special operator can determine whether enough primary trunks are provided, or whether enough operators are on duty to handle the traffic.

Of course, it naturally follows that these 55 meters can be placed in various positions to indicate the condition of the various pieces of apparatus in the exchange.

Having thus described the invention what is claimed as new is:

- 60 1. In a telephone exchange system, the combination of calling subscribers' lines, a plurality of lines common to a single called subscriber, means for interconnecting the calling and called subscribers' lines including automatic switches in which the lines

terminate, means for directing the action of the switches, and means including a repeating relay for predeterminedly operating an automatic switch or automatically in order to select another of said plurality of lines 70 when the line selected is busy.

2. In a telephone exchange system, the combination of calling subscribers' lines, a plurality of lines common to a single called subscriber, means for interconnecting the calling and called subscribers' lines including automatic selector and connector switches, the plurality of lines terminating in a connector switch, means for directing the action of the switches to select the line 75 wanted, and means for actuating the connector switch predeterminedly or automatically in order to select another of said plurality of lines when the line selected is busy, 80 said actuating means in both instances comprising a magnet for operating the switch, a repeating relay for operating the magnet, and means for interrupting the circuit of the repeating relay.

3. In a telephone exchange system, the combination of a calling subscriber's line, a plurality of lines common to a single called subscriber, means for interconnecting the calling and called subscribers' lines comprising automatic switches in which the lines terminate, means for operating the switches, means for directing the action of the operating means including a repeating relay arranged to actuate the operating means, and another relay adapted to energize the repeating 95 relay when the line selected is busy.

4. In a telephone exchange system, the combination of calling subscribers' lines, of a plurality of lines common to a single called subscriber, means for interconnecting the calling and called subscribers' lines including automatic selector and connector switches in which the lines terminate, means for operating the switches, impulse sending-means for directing the action of the operating 105 means, a relay normally responsive to the impulse sending-means, means for automatically operating said relay when a busy line is selected to actuate the operating means of the connector switch and select another of 110 said plurality of lines.

5. In a telephone exchange system, the combination of calling subscribers' lines, a plurality of lines common to a single called subscriber, means for interconnecting the calling and called subscribers' lines including automatic selector and connector switches in which the lines terminate, means for operating the switches, means for directing the action of the operating means, 120 a repeating relay arranged to actuate the operating means for the connector switch, and a relay arranged to operate the repeating relay and connector switch operating means so that another of said plurality of lines will 125 130

be automatically selected when the line selected is busy.

6. In a telephone exchange system, the combination of calling subscribers' lines, a plurality of lines common to a single called subscriber, means for interconnecting the calling and called subscribers' lines including automatic selector and connector switches in which the lines terminate, step by step operating means for the switches, impulse-sending means for directing the action of the switches, a repeating relay responsive to impulses from the impulse-sending means to actuate the switch operating means, and a relay rendered operative to actuate the repeating relay, and cause the operating means to step and select another of said plurality of lines when the line selected is busy, and means for rendering the last-named relay inoperative when an idle line is selected.

7. In a telephone exchange system, the combination of subscribers' lines, part of said lines terminating at a private branch exchange, means for interconnecting the lines including automatic selector and connector switches, private branch exchange trunk lines, said private branch exchange trunk lines also terminating at the connector switches, means for directing the action of the switches and for actuating a connector switch selected to select a trunk line leading to the private branch exchange, and means including a repeating relay for predeterminedly operating the connector switch or for automatically continuing the operating of the connector switch to select a succeeding trunk line when the line it first selects is busy.

8. In a telephone exchange system, the combination of subscribers' lines, part of said lines terminating at a private branch exchange, means for interconnecting the lines including automatic selector and connector switches, private branch exchange trunk lines, means for directing the action of the switches and for actuating a connector switch to select a trunk line leading to the private branch exchange, and means including a repeating relay associated with the connector switch, directive actuating means and rendered automatically operative when the connector switch selects a busy trunk line leading to the private branch exchange for again operating the connector switch.

9. In a telephone exchange system, the combination of calling subscribers' lines, a plurality of lines common to a single called subscriber, means for interconnecting the calling and called subscribers' lines including selector and connector switches provided with banks of contacts in which the lines terminate, a plurality of lines terminating in a series of contacts of a bank in the connector switches, operating means for the

switches, impulse sending-means for directing the action of the operating means, a relay, said relay normally responsive to the impulse sending-means for predeterminedly actuating the operating means of the connector switch, to select any one of the plurality of lines, and means for automatically operating said relay to cause the selection of another of said lines in case the line selected is busy.

10. In a telephone exchange system, a plurality of lines common to a single called subscriber, means for extending connections to such lines including ordinary and special connector switches, means for electrically distinguishing busy ones of said lines from idle ones, means individual to the ordinary connector switches responsive to an electrical condition designating a busy line for restoring such switches, and means individual to the special connector switches responsive to the same electrical condition for advancing such switches to other of such plurality of lines.

11. In a telephone exchange system, the combination of calling subscribers' lines, a plurality of lines common to a single called subscriber, means for interconnecting the calling and called subscribers' lines including sets of automatic selector and connector switches, the plurality of lines terminating in a series of contacts in a special connector switch and being multiplied into contacts in the other connector switches, impulse-sending means for directing the action of the interconnecting means, a trunk line comprising only two wires connecting two different sets of automatic switches and over which impulses may be transmitted, and means for operating the special connector switch to select another of said plurality of lines when the line selected is busy independently of said impulse sending means.

12. In a telephone exchange system, the combination of calling subscribers' lines, a plurality of lines common to a single subscriber, means for interconnecting the lines including first selector switches, trunk selector switches, a special connector switch having a series of contacts at which the plurality of lines terminate and other connector switches into which the plurality of lines are multiplied, a two wire trunk line connecting the first selector and trunk selector switches, means including a device for sending impulses over the two wire trunk for directing the operation of said switches to connect the line calling with any particular one of said plurality of lines, and means for actuating the special connector switch to select the first idle one of said plurality of lines.

13. In a telephone exchange system, the combination of a subscriber's line circuit, an operator's equipment, means for connecting

the line circuit to the operator's equipment, and means controlled by the operator for disconnecting the line circuit and maintaining the same in inoperative condition independent of the connecting means.

14. In a telephone exchange system, the combination of subscribers' lines, an operator's equipment, mechanism including a means individual to each of said lines for connecting the subscriber's lines to the operator's equipment, and means controlled by the operator for disabling the connecting means individual to any one of said lines and maintaining the same in a disabled condition independent of the rest of the mechanism.

15. In a telephone exchange system, the combination of subscribers' lines, an operator's equipment, means for connecting the lines to the operator's equipment including a relay and its control circuit individual to each of said lines, and a second relay controlled by the operator for altering the circuit of any one of the individual relays to disconnect the subscribers' lines at will, the said second relays thereafter being controlled over the subscribers' lines.

16. In a telephone exchange system, the combination of a subscriber's line circuit, an operator's equipment, means responsive to an alteration of the line circuit for connecting the line to the operator's equipment, and means controlled by the operator for disconnecting the subscriber's line and maintaining the same in inoperative condition independent of the connection means.

17. In a telephone exchange system, the combination of subscribers' lines, mechanism for interconnecting the lines including automatic switches, means individual to each line for rendering such line unselectable in such switches, restoring means for said switches, means for operating the individual means of any line through the medium of said automatic switches, and additional means for maintaining the individual means of said line in operation after the restoration of said switches.

18. In a telephone exchange system, the combination of subscribers' lines, mechanism for interconnecting the lines, means individual to each of the lines operative upon the initiation of a call to actuate said mechanism, restoring means for said mechanism, and means for rendering the individual means of any line unresponsive to the initiation of a call by the medium of said interconnecting mechanism, and additional means for maintaining said individual means unresponsive to the initiation of a call after the restoration of said mechanism.

19. In a telephone exchange system, the combination of subscribers' lines, mechanism for interconnecting the lines including means common to a group of lines, and

means individual to each of the lines operative upon the initiation of a call to actuate the common means, means exercised over said common means at will for rendering the individual means inoperative, and additional means for maintaining said individual means inoperative after restoring to normal the common means.

20. In a telephone exchange system, the combination of a subscriber's line, an operator's position, means for connecting the line to the operator's position on initiation of the call by the subscriber or upon the alteration of the subscriber's line by a ground or short circuit thereon, and means for disabling said line over the connecting means, additional means for maintaining the line in a disabled condition after the restoration of the connecting means.

21. In a telephone exchange system, the combination of a subscriber's line, an operator's position and equipment, means for connecting the subscriber's line to the operator's position and equipment, a device for initiating the operation of said connecting means individual to said line, means for disabling said device over said connecting means, and additional means individual to the line for maintaining said device in a disabled condition.

22. In a telephone exchange system, the combination of a plurality of subscribers' stations and lines, an operator's position and equipment, means for interconnecting the lines and stations including mechanism common to a group of lines, a device individual to each of the lines actuated when the electrical condition of the subscriber's line is altered, means for connecting a calling subscriber's line to the operator's position when said device is actuated, and means controlled by the operator for disabling said device at will exercised over said connecting means and restoring the said mechanism in condition to be operated by another line calling, the said individual device remaining disabled after the restoration of said mechanism.

23. In a telephone exchange system the combination of subscribers' lines and stations, means for interconnecting the lines including automatic switches in which said lines terminate, an operator's position and equipment, means for connecting the lines to the operator's position and equipment, mechanism common to a plurality of lines for actuating one of said switches, a device individual to each of said lines for actuating said mechanism upon the initiation of a call or by the accidental short circuiting or grounding of the line, means controlled by the operator exercised over the connecting means for disabling any one of the devices and restoring the mechanism actuated thereby and maintaining the device inoperative.

- tion of the switching mechanism to interconnect the lines, key set switches, trunk lines terminating at the manual switchboard and in the key set switches, operating means 5 for the key set switches including a starting relay, a circuit for energizing said starting relay, and means including a magnet for disabling said circuit whereby the trunk calling may not become connected to the key 10 set switch disabled.
19. In a telephone exchange system, the combination of a first operator's position, calling subscribers' lines terminating at the first operator's position, a second operator's 15 position, a keyboard and key sets at the second operator's position, calling subscribers' lines terminating at the second operator's position, means for interconnecting the subscribers' lines operable from the second operator's position, automatic switches associated with the second operator's position, trunk lines terminating at the first operator's position and in the automatic switches and second operator's position, and 20 means for operating the automatic switches comprising starting means, a circuit for controlling said starting means and means controllable by the second operator for controlling said circuit.
20. In a telephone exchange system, the combination of a calling subscriber's line, a called subscriber's line, switching mechanism for interconnecting the lines including an automatic switch, releasing means 25 for said switch, and means independent of any of the circuits of the line called for preventing the operation of said releasing means.
21. In a telephone exchange system, the combination of a calling subscriber's line, a called subscriber's line, switching mechanism for interconnecting the lines including automatic switches, means for releasing the switches, and means independent of any 30 of the circuits of the line called for preventing the operation of said releasing means at will.
22. In a telephone exchange system, the combination of a calling subscriber's line, a called subscriber's line, switching mechanism including an automatic switch for interconnecting said lines, an operator's position, means at said position for directing the operation of said automatic switch, 35 means for releasing said automatic switch, the operation of said releasing means depending upon the position assumed by said switch under the influence of said directing means.
23. In a telephone exchange system, the combination of a calling subscriber's line, a called subscriber's line, means for interconnecting the lines including automatic switching mechanism, an operator's position, means for releasing the switching 40
- mechanism, and means at the operator's position for directing the action of the switching mechanism and disabling said releasing means at will.
24. In a telephone exchange system, the combination of a calling subscriber's line, a called subscriber's line, automatic switching mechanism for interconnecting the lines including a primary switch and a first selector switch, releasing means for the 45 switches, an operator's position, means for directing the operation of the switching mechanism and for preventing the release of said switches at will.
25. In a telephone exchange system, the combination of a calling subscriber's line, a called subscriber's line, switching mechanism for interconnecting the lines including a primary automatic switch and connector switch, means for releasing the primary switch, means for directing the operation of the switching mechanism, and means independent of any of the circuits of the called line for disabling said releasing 50 means at will.
26. In a telephone exchange system, the combination of a calling subscriber's line, a called subscriber's line, switching mechanism for interconnecting the lines including an automatic switch having banks of contacts, certain of contacts being special and without connection to said lines, releasing means for said automatic switch and means for operating the automatic switch to connect the releasing means with the special contacts whereby the releasing 55 means is disabled.
27. In a telephone exchange system, the combination of a calling subscriber's line, a called subscriber's line, switching mechanism for interconnecting the lines including an automatic selector switch having open contacts, an operator's position, releasing means for the selector switch including a circuit terminating in said switch, and means for directing the operation of the switching mechanism to connect said circuit to the open contacts whereby the releasing means is disabled.
28. In a telephone exchange system, the combination of a calling subscriber's line, a called subscriber's line, switching mechanism for interconnecting the lines, including an automatic switch having banks of contacts therein, the contacts of one of said 60 banks being normally open, signaling means connected to another bank of contacts, releasing means for the automatic switch, and means for directing the operation of the switch so as to connect the releasing means to an open contact and disable the same and simultaneously operate said signaling means.
29. In a telephone exchange system, the combination of a calling subscriber's line, 65

operator's equipment and including means common to the group of lines and means individual to each of said lines, and a device associated with the means common to the group for indicating at any instant the number of active lines in said group.

33. In a telephone exchange system the combination of groups of subscribers' lines, an operator's position and equipment, means for interconnecting the lines and temporarily connecting the lines to the operator's position comprising automatic switches, mechanism common to each group including a group relay for actuating one of said switches when one of the lines in the group is rendered active, and a device in circuit with the group relay calibrated to indicate the number of active lines in the group with which it is associated.

34. In a telephone exchange system the combination of subscribers' lines, an operator's position and equipment, means for interconnecting the lines including automatic switches in which said lines terminate, means for temporarily and successively connecting the lines to the operator's position and equipment comprising other automatic switches, and means associated therewith for indicating the number of active lines waiting to be connected to the operator's position and equipment.

35. In a telephone exchange system, the combination of subscribers' lines, an operator's position and equipment, means for interconnecting the lines including automatic switching mechanism in which the lines terminate, automatic switches associated with the operator's position and equipment, trunk lines terminating in the automatic switches and adapted to be connected to the subscribers' lines, and means comprising a single movable device adapted to assume a position corresponding to and for visually indicating the number of trunk lines active at any instant.

36. In a telephone exchange system, the combination of subscribers' lines, an operator's position and equipment including a key set, means common to a group of lines for connecting the lines to the operator's position and equipment, means individual to each line and rendered operative when a line circuit is altered to actuate the common connecting means, means for disabling the individual means and maintaining the same in inoperative condition, and a key in the key set for manually controlling the disabling means.

37. In a telephone exchange system the combination of separate telephone exchanges, calling subscribers' lines terminating at one exchange, called subscribers' lines terminating at the remote exchange, automatic switching mechanism for interconnecting the lines including the first selector switch at

the first mentioned exchange, and selector and connector switches at the remote exchange, an operator's position and equipment arranged to be connected to the lines, means controlled by the operator for directing the action of the automatic switching mechanism including an impulse sending device, and a trunk line comprising only two wires extending between the selector switch in the first exchange and the switches in the remote exchange and over which the impulses may be transmitted, means for restoring the switching mechanism including a relay timed to guard the trunk line busy during the restoration of the switch at the remote exchange.

38. In a telephone exchange system, the combination of a calling subscriber's line, a called subscriber's line, means for interconnecting the lines including first selector, trunk selector and connector switches, means for directing the action of the automatic switching mechanism including an impulse sending device, a trunk line connecting the first selector and second selector switches and comprising only two wires over which the impulse may be transmitted, and means for restoring the switches including means for rendering the trunk line busy during the restoration of the trunk selector switch.

39. In a telephone exchange system, the combination of a calling subscriber's line, a called subscriber's line, automatic switching mechanism for interconnecting the lines including trunk selector switches and means for selecting a trunk selector, an operator's position and equipment adapted to be connected to the lines, means for directing the action of the automatic switching mechanism including an impulse sending device, a trunk line comprising but two wires arranged to connect the trunk selector to its selecting means and over which the impulses may be transmitted to direct the action of the trunk selector switch, means for restoring the switches comprising means timed for guarding against the action of the selecting means until after the trunk selector switch is restored.

40. In a telephone exchange system, the combination of calling and called subscribers' lines, means for interconnecting the lines including groups of selector switches, impulse sending means for directing the action of the switches to interconnect the lines, a trunk line comprising only two wires for connecting two groups of selector switches and over which the impulses are transmitted, means for restoring the switches on the conclusion of a call including means for rendering the trunk line busy during the restoration of the switches.

41. In a telephone exchange system the combination of calling and called subscribers' lines, mechanism for interconnecting

the lines including automatic selector and connector switches, and a two-wire trunk line between two sets of said switches, means for directing the action of the switches including an impulse sending means, and means for restoring the switches including mechanism timed for preventing the selection of the trunk line until after the restoration of the trunk selector switch.

10 42. In a telephone exchange system, the combination of telephone exchanges, subscribers' lines, part of the lines terminating in one exchange and part terminating at another exchange, automatic switching mechanism including first selector, trunk selector and connector switches for interconnecting the lines, an operator's position and equipment, means for connecting the latter to the lines, means controlled by the operator for 20 directing the action of the automatic switches including an impulse-sending device, the trunk selector and connector switches being located at one of the exchanges and the selector switch being located at another exchange, a two-wire trunk line extending between the exchanges and connecting the first selector and trunk selector switches, means for restoring the switching mechanism including means at one exchange for simultaneously grounding both wires of the two-wire trunk and timed to guard said two-wire trunk until after the release of the trunk selector switch.

43. In a telephone exchange system, the combination of separate telephone exchanges, subscribers' lines, part of the lines terminating at one exchange and part terminating at another exchange, mechanism for interconnecting the lines including trunk selector and connector switches at one exchange, and first selector switches at the other exchange arranged to select an idle trunk selector, an operator's position and equipment, means for connecting the latter with the lines, means for directing action of the automatic switches including an impulse sending device, a trunk line connecting the first selector switches with the trunk selector switches and over which the impulses may be transmitted and the release of the switching mechanism may be exercised, means rendered active when the first selector selects an idle trunk selector for guarding the trunk line after the restoration of the first selector and until after the restoration of the trunk selector.

44. In a telephone exchange system, the combination of telephone exchanges, calling subscribers' lines terminating in one exchange, called subscribers' lines terminating at another exchange, mechanism for interconnecting the lines including first selector switches at one exchange and trunk selector and connector switches at the other exchange, an operator's position and equip-

ment, means for connecting the latter to the lines, means for directing the operation of the automatic switches including an impulse sending means, a trunk line comprising only two wires extending between the exchanges and over which the impulses may be transmitted to operate the switches in the other exchange, electrically operated means associated with the first selector switches and rendered operative when the first selector switch picks out an idle trunk selector for rendering the selector switch busy against other calls, means for restoring the switches, said electrically operated means being arranged to hold the trunk line busy until the trunk selector restores.

45. In a telephone exchange system, the combination of subscribers' calling and called lines, means for interconnecting the lines including groups of automatic switches in which the lines terminate, means including an impulse sending device for directing the operation of the switches, a special trunk line comprising only two wires extending between two groups of switches and over which the impulses may be transmitted to operate the succeeding switches, means responsive to impulses sent over the special trunk line wires for operating the succeeding switches comprising electrically operated means normally connected to the selected trunk lines, condensers normally in series with the trunk lines, and means responsive to the electrically operated means for short circuiting the condensers while impulses are being transmitted to operate a succeeding switch, and arranged to reconnect the condensers in series with the trunk lines when the called subscriber answers.

46. In a telephone exchange system, the combination of subscribers' calling and called lines, means for interconnecting the lines including groups of automatic switches, a special trunk line comprising only two wires extending between two groups of switches, means including an impulse sending device for directing the operation of the switches at one end of the special trunk line and the succeeding switches over the special trunk line, means responsive to impulses sent over one of the special trunk wires for operating one of a group of succeeding switches, condensers connected in series with the trunk wires of the succeeding switch selected, means responsive to impulses sent over one of the wires of said special trunk line for short circuiting the condensers so that the succeeding impulses may direct the operation of another automatic switch adapted to connect the wanted line to the line calling, and means for reinserting the condensers in series with the trunks when the called subscriber answers.

47. In a telephone exchange system, the combination of subscribers' calling and

- called lines, means for interconnecting the lines including first selector, second or trunk selector and connector switches, means including an impulse sending device for directing the operation of the switches, a special trunk line composed of only two wires extending between the first selector and trunk selector switches and over which the impulses may be transmitted to operate the second or trunk selector and connector switches, condensers normally in series with lines leading to said trunk selector, means responsive to impulses sent over the special trunk line for operating the trunk selector and for short circuiting the condensers so that the impulses may direct the operation of the connector switch, means acting after the last test impulse for reinserting the condensers in circuit.
48. In a telephone exchange system, the combination of telephone exchanges, subscribers' lines part of which terminate at one exchange, the other of said lines terminating at a distant exchange, means for interconnecting the lines including automatic switches at the distant exchange, automatic switches at the first mentioned exchange for selecting an idle switch at the distant exchange, means including an impulse sending device for directing the operation of the switches, a special trunk composed of only two wires extending between the exchanges and over which the impulses may be transmitted to operate the switches at the other exchange, means at a distant exchange responding to impulses sent over said special wires for operating switches at the distant exchange to establish connection of the calling with the called subscriber, condensers normally in series with lines terminating in switches at the distant exchange, means for short circuiting the condensers, and means acting after the last impulse transmitted for reinserting the condensers in circuit.
49. In a telephone exchange system, the combination of subscribers' calling and called lines, means for interconnecting the lines including automatic switches and link circuits, means including an impulse sending device for directing the operation of the switches, condensers normally in series with lines leading to certain switches, means responsive to impulses sent over the lines for short circuiting the condensers so that the impulses may direct the operation of the succeeding mechanism, means acting after the last impulse sent for reinserting the condensers in circuit.
50. In a telephone exchange system, the combination of subscribers' calling and called lines, means for interconnecting the lines including automatic switches and link circuits, impulse sending means for directing the operation of the switches, condensers normally in series with lines leading to cer-

tain switches, means for short circuiting the condensers so that impulses may direct the operation of the succeeding mechanism, and means for reinserting the condensers in the circuit comprising a relay operated by the final impulse transmitted, a second relay and means whereby said second relay is rendered operative when the first-mentioned relay is energized.

51. In a telephone exchange system, the combination of subscribers' calling and called lines, means for interconnecting the lines including selector switches, connector switches and link circuits, impulse sending means, repeating relays associated with the switches and responsive to the impulse sending means for directing the operation of the switches, condensers normally in series with lines leading to certain switches, means for short circuiting the condensers so that the impulses may direct the operation of the succeeding mechanism for interconnecting the lines, and means for reinserting the condensers in series with their respective lines rendered operative by the actuation of one of said repeating relays when the final test impulse is transmitted.

52. A telephone exchange system, the combination of subscribers' calling and called lines, means for interconnecting the lines including selector switches, connector switches and link circuits, condensers normally in series with the lines of said link circuits, impulse sending means, repeating relays associated with the switches and responsive to impulse sending means for directing the operation of the switches, other relays associated with certain switches and adapted to short circuit the condensers of the line selected so that the subsequent impulses may direct the operation of the succeeding mechanism, and means for reinserting the condensers in the circuit arranged to be operated after the final impulse transmitted operates a repeating relay and thereby deenergizes said other relay.

53. In a telephone exchange system, the combination of subscribers' calling and called lines, means for interconnecting the lines including first selector, second or trunk selector and connector switches, means including an impulse sending device for directing the operation of the switches, a special trunk line composed of only two wires extending between the first selector and trunk selector switches and over which the impulses may be transmitted to operate the second or trunk selector and connector switches, condensers normally in series with lines leading to said trunk selector, means responsive to impulses sent over the special trunk line for operating the trunk selector and for short circuiting the condensers so that the impulses may direct the operation of the connector switch, means responding

when the called subscriber answers for reinserting the condensers in circuit.

54. In a telephone exchange system, the combination of subscribers' calling and called lines, means for interconnecting the lines including first selector, second or trunk selector and connector switches, means including an impulse sending device for directing the operation of the switches, a special 10 trunk line composed of only two wires extending between the first selector and trunk selector switches and over which the impulses may be transmitted to operate the second or trunk selector and connector switches, condensers 15 normally in series with lines leading to said trunk selector, means responsive to impulses sent over the special trunk line for operating the trunk selector, said means for cutting out the condensers comprising a repeating 20 relay normally tied to one of said lines leading to the trunk selector switch and operable at the beginning of a certain group of impulses sent by said impulse sending means, and means for reinserting the condensers 25 in series with said lines when the called subscriber answers, and means for restoring the switches at the conclusion of the call.

55. In a telephone exchange system, the combination of subscribers' calling and called lines, means for interconnecting the lines including first selector, second or trunk selector and connector switches, means including an impulse sending device for directing the operation of the switches, a special 30 trunk line composed of only two wires extending between the first selector and second selector switches and over which the impulses may be transmitted to operate the second or trunk selector and connector switches, means responsive to impulses sent over one of said special trunk wires for operating the trunk selector, means responsive to impulses sent over the other wire arranged to provide a path for the transmission of impulses, means for disabling the foregoing means responsive to the impulses when the called subscriber answers, and means for restoring the responsive means 40 and switches to normal position when the call is concluded.

56. In a telephone exchange system, the combination of subscribers' calling and called lines, means for interconnecting the lines including a first selector, second or trunk selector and connector switches, means including a device for sending groups of impulses for directing the operation of the switches, a special trunk comprising only 50 two wires extending between the first selector and second or trunk selector over which the groups of impulses may be transmitted, condensers connected in series with lines terminating in the trunk selector, 55 means normally connected to one of said

lines and responsive to the first group of impulses transmitted over the special trunk for actuating the trunk selector, means normally connected to the other line and responsive to the second group of impulses 70 for short circuiting the condensers in both lines so that the succeeding impulses may direct the operation of the connector switch, and means responding when the called subscriber answers for reinserting the condensers 75 in series with said lines.

57. In a telephone exchange system, the combination of calling and called subscribers' lines, means for interconnecting the lines including automatic first selector, second or trunk selector and connector switches, means for directing the action of the automatic switches including a device for sending groups of impulses, a special 80 trunk composed of only two wires extending between the first selector and second selector switches and over which the impulses may be transmitted to operate the second selector and connector switches after the first selector has selected an idle second selector 85 and is rendered busy, a repeating relay normally connected to a line terminating in the second selector selected and responsive to the first group of impulses sent over one of said special trunk wires for starting the 90 operation of the second selector, a second repeating relay normally connected to another line terminating in said second selector switch and responsive to the second group of impulses sent over the other special trunk 95 wire, and arranged to provide a path to permit succeeding groups of impulses to be transmitted to operate the connector switch, and means for restoring said switches and 100 relays to normal condition when the call is 105 concluded.

58. In a telephone exchange system, the combination of calling and called subscribers' lines, means for interconnecting the lines including automatic first selector, second or 110 trunk selector and connector switches, means for directing the action of the automatic switches including a device for sending groups of impulses, a special trunk composed of only two wires extending between the first selector and second selector switches and over which the impulses may be transmitted to operate the second selector and connector switches after the first selector has selected an idle second selector and is rendered busy, 115 a set of repeating relays normally connected to lines terminating in the second selector selected, said set of relays being temporarily disabled while impulses are being transmitted over said special trunk wires and the 120 lines with which the relays are associated to operate the succeeding mechanism, means for rendering the relays again in condition to be actuated when the called subscriber answers or when the calling subscriber hangs 125 130

up his receiver, and means for restoring the automatic switches when the call is concluded.

59. In a telephone exchange system, the combination of calling and called subscribers' lines, means for interconnecting the lines including automatic first selector, second or trunk selector and connector switches, means for directing the action of the automatic switches including a device for sending groups of impulses, a special trunk composed of only two wires extending between the first selector and second selector switches and over which the impulses may be transmitted to operate the second selector and connector switches after the first selector has selected and idle second selector and is rendered busy, a first repeating relay normally connected to a line terminating in the second selector selected and responsive to the first group of impulses send over one of said special trunk wires for starting the operation of the second selector, a second repeating relay normally connected to another line terminating in said second selector switch and responsive to the second group of impulses sent over the other special trunk wire, and arranged to provide a path to permit succeeding groups of impulses to be transmitted to operate the connector switch, said second relay temporarily opening the circuit of the lines with which said repeating relays are associated, said first relay being temporarily disabled by the first impulse of the third group of impulses which operate the succeeding switch, said second repeating relay being temporarily disabled by the first impulse of the fourth group, whereupon the first relay is rendered in condition to be operated, the said first relay being operated by the first impulse of the fifth group rendering the second relay again in condition to be operated, the second relay being disabled by the last impulse and rendering the first relay again in condition to be operated, means for rendering the second relay in condition to be operated and for breaking said path provided for the impulses when the called subscriber answers, and means for restoring the switches when the call is concluded.
60. In a telephone exchange system, the combination of calling and called subscribers' lines, means for interconnecting the lines including automatic selector switches, means for directing the action of the switches including a device for sending groups of impulses, a special trunk line comprising only two wires extending between two different groups of selector switches and over which the impulses may be transmitted to operate the succeeding switches, the impulse sending device being associated with one of said groups of switches, lines leading to the first selector switch beyond the special trunk line, condensers in series with said lines, means

including a set of repeating relays associated with the lines arranged to actuate the switching mechanism and to short circuit the condensers to provide a path over which the impulses may be transmitted to operate the succeeding switches, means for restoring the relays and switches to normal condition when the call is concluded comprising a quick acting and a slow acting relay which are released and simultaneously connect ground to the link circuit connecting the subscribers, the slow acting relay being arranged to prevent the selector switch preceding the special two wire trunk selecting said trunk until after the restoration of the succeeding switch. 70 75 80

61. In a telephone exchange system, the combination of calling and called subscribers' lines, automatic switching mechanism for interconnecting lines including selector and connector switches, means for directing the action of the switches including a device for sending impulses, a special trunk line comprising only two wires extending between two different groups of switches and over which the impulses may be transmitted to operate the succeeding switches, means for restoring the mechanism to normal position including a quick acting and a slow acting relay arranged to simultaneously ground the special trunk wires, 90 the slow acting relay being arranged to prevent the selection by the first selector switch set until after the restoration of the succeeding switch. 95

62. In a telephone exchange system, the combination of subscribers' calling and called lines, means for interconnecting the lines including first selector, second or trunk selector and connector switches, means including an impulse sending device for directing the operation of the switches, a special trunk line composed of only two wires extending between the first selector and trunk selector switches and over which the impulses may be transmitted to operate the second or trunk selector and connector switches, condensers normally in series with lines leading to said trunk selector, means responsive to impulses sent over the special trunk line for operating the trunk selector and for short circuiting the condensers so that the impulses may direct the operation of the connector switch, means responsive to the last test impulse for reinserting the condensers in circuit. 100 105 110 115

63. In a telephone exchange system, the combination of telephone exchanges, subscribers' lines part of which terminate at one exchange, the other of said lines terminating at a distant exchange, means for interconnecting the lines including automatic switches at the distant exchange, automatic switches at the first mentioned exchange for selecting an idle switch at the distant exchange, means including an impulse sending 120 125 130

device for directing the operation of the switches, a special trunk composed of only two wires extending between the exchanges and over which the impulses may be transmitted to operate the switches at the other exchange, means at a distant exchange responding to impulses sent over said special wires for operating switches at the distant exchange to establish connection of the calling with the called subscriber, condensers normally in series with lines terminating in switches at the distant exchange, means for short circuiting the condensers, and means responsive to the last impulse transmitted for reinserting the condensers in circuit.

64. In a telephone exchange system, the combination of subscribers' calling and called lines, means for interconnecting the lines including automatic switches and link circuits, means including an impulse sending device for directing the operation of the switches, condensers normally in series with lines leading to certain switches, means responsive to impulses sent over the lines for short circuiting the condensers so that the impulses may direct the operation of the succeeding mechanism, means responsive to the last impulse sent for reinserting the condensers in circuit.

65. In a telephone exchange system, the combination of subscribers' calling and called lines, means for interconnecting the lines including selector switches, connector switches and link circuits, condensers normally in

series with the lines of said link circuits, 35 impulse sending means, repeating relays associated with the switches and responsive to impulse sending means for directing the operation of the switches, other relays associated with certain switches and adapted to 40 short circuit the condensers of the line selected so that the subsequent impulses may direct the operation of the succeeding mechanism, and means for reinserting the condensers in the circuit arranged to be operated when the final impulse transmitted operates a repeating relay and thereby deenergizes said other relay.

66. In a telephone exchange system, the combination of calling subscribers' lines, a 50 plurality of lines common to a single called subscriber, means for interconnecting the calling and called lines including automatic switches in which the lines terminate, means 55 for predeterminedly operating an automatic switch for selecting a certain one of the plurality of lines common to a called subscriber, and means for predeterminedly operating another automatic switch for automatically selecting the first idle one of said plurality 60 of lines.

In testimony whereof I affix my signature in presence of two witnesses.

JOSEPH L. WRIGHT.
